LOCK TOP CONTAINER

Frank J. O'Brien, Pelham Manor, N. Y., assignor
to Continental Can Company, Inc., New York,
N. Y., a corporation of New York

Application December 28, 1944, Serial No. 570,185

2 Claims. (Cl. 220—73)

1

The present invention relates to improvements in metal containers, and more particularly to a metal container having a lock top closure therefor.

An important object of the invention, is to provide the upper end of the container with a smooth even surface to facilitate sealing when the closure is positioned thereon.

Another object of the invention is to provide the upper end of a container with a double seamed collar or ring for the purpose of producing a relatively wide smooth and even sealing surface for a compound lined cover or top.

A further object of the invention is to provide a container of the above type wherein the collar or ring fits within the upper end of the container and is double seamed thereon to form a rigid, smooth surface around the top edge of the container to facilitate sealing when the closure is applied thereto.

The above and other objects of the invention will in part be obvious and will in part be hereinafter more fully pointed out.

In the drawing:

Figure 1 is a side elevational view, partly in section, of a container embodying the features of the present invention.

Figure 2 is an enlarged fragmentary detail sectional view illustrating the position of the ring relative to the container prior to the double seaming operation.

Figure 3 is a similar view after the double seaming operation has been performed.

Figure 4 is an enlarged fragmentary detail sectional view with the cover locked on the container.

In the manufacture of containers, it is essential that closure means be provided which will tightly seal the open end of the container. In metal containers, such as cans, it is conventional to employ a side seam extending longitudinally through the length of the can and including a lapped portion at least at the upper end portion of the seam, and when the upper edge of the can is rolled to form a seat for a closure, this double thickness lap seam creates an open space or uneven surface through which leakage is liable to occur. In order to obviate this possibility, the present container is provided with a seamless ring which is rolled on the top edge of the container to form a smooth even surface for a compound lined cover.

Referring to the drawing for a more detailed description thereof, the improved container is generally designated by the reference numeral 5

2

and comprises a body portion 6 to which a bottom end 7 is secured in the usual manner. The body portion 6 is preferably cylindrical and its upper end 8 is left open and is adapted to be closed by means of the lock top or cover generally designated by the reference character A.

The upper end 8 of the body portion is offset inwardly to form a shoulder 9 and an annular rim 10. The rim 10, during the fabrication of the container, is formed with a flange 11 extending at right angles thereto, adapted to be bent downwardly during the seaming operation. A drawn metal ring 12 is positioned within the upper end of the body portion 6 being confined by the annular rim 10 thereof, which ring is formed with a flange 13 extending at right angles to the container and substantially parallel with the flange 11, as shown in Figure 2. After positioning the ring within the container a spinning operation is performed in order to cause the lower end 14 to follow the shape and contour of the shoulder 9 and at the same time be brought into tight bearing engagement with the entire upper end of the body portion.

25 The container 6 with the ring 12 firmly held therein is then subjected to a double seaming operation to provide the construction shown in Figure 3. By this double seaming operation the flange 11 is bent downwardly to a position substantially parallel with the rim 10 and the flange 13 is bent downwardly and upwardly so that the end 14 thereof is positioned between the down-turned flange 11 and rim 10 as clearly shown in Figure 3. This double seaming of the ring 12 on the upper end of the container provides a more rigid construction and at the same time produces a relatively wide, smooth and even surface 15 for the closure A to be sealed thereon. In other words, there are no stepped or uneven surfaces 30 which would tend to produce a faulty seal when a lock top closure is applied to the upper edge of the container.

The type of closure used with the new and improved container is well known in the art and 45 generally comprises a body 16 that is depressed centrally to form a central body portion 17 and a heel 18 which fits within the ring 12 and cooperates with the skirt portion 19 in forming an annular channel 20. The skirt 19 is dimensioned 50 to fit closely about the body wall of the container, and the end thereof is bent outwardly and inwardly at right angles to form an annular stiffener hem 21. The annular channel 20 carries a sealing compound B for sealing the contents of the container when the cover is locked

thereon. The cover is locked on the container through the medium of the spaced thread portions 22 formed on the body just below the offset 9 and which are engaged by complementary thread portions 23 formed on the cover. A slight rotation of the cover will cause the thread portions 23 to engage the thread portions 22 for locking the cover in position on the upper end of the container.

With the cover in locked position, the sealing compound 19 will follow the contour of the surface 15, which surface is smooth and rigid, for effectively sealing the contents of the container. The upper end of the container is reinforced by reason of the double seamed ring thus withstanding considerable pressure in the application of the closure without any appreciable distortion. The surface 15 is sufficiently wide and smooth to accommodate the sealing compound held within the channel 20 so that the contents of the container will be effectively sealed.

While a preferred embodiment of the invention has been shown and described, it is to be understood that the invention is not limited to the illustrated embodiment but may be variously modified without departing from the spirit and scope of the invention as defined in the appended claims.

What I claim is:

1. A metal container comprising a body having an open upper end, a drawn metal ring fitting within the open end of said body and extending outwardly over the body wall and rolled into a double seam with the body wall, said drawn

metal ring forming at the upper end of the seam a continuous unbroken rounded sealing surface, a closure for said container, said closure having a central depression surrounded by a cylindrical wall and a depending skirt spaced outwardly from said cylindrical wall and joined thereto by a curved portion conforming to the curvature of the sealing surface on the drawn ring, a sealing gasket disposed in said closure and engaging the sealing surface on the ring, and means for mechanically securing the skirt of the closure member to the body of the container for holding said closure member in sealing contact with the body.

2. A metal container comprising a body having an open upper end, said open end portion being offset inwardly forming in said body a shoulder, a drawn metal ring fitting within the open end of the body and closely contacting said shoulder, said metal ring being extended outwardly over the body wall and rolled into a double seam with the body wall, said drawn metal ring forming at the upper end of the seam a continuous unbroken rounded sealing surface, a closure for said container, said closure having a central depression surrounded by a cylindrical wall and a depending skirt spaced outwardly from said cylindrical wall and joined thereto by a curved portion conforming to the curvature of the sealing surface on the drawn ring, a sealing gasket disposed in said closure and engaging the sealing surface on the ring, said depending skirt being extended below the shoulder in the body wall and having a threaded connection with said body wall.
